F. S. McATEE

SUPPLEMENTAL AIR VALVE

Filed Sept. 19, 1922

Inventor

F. S. McAtee.

By *Browne & Phelps*

Attorney

UNITED STATES PATENT OFFICE.

FRED S. McATEE, OF LINCOLN, NEBRASKA.

SUPPLEMENTAL AIR VALVE.

Application filed September 19, 1922. Serial No. 589,164.

To all whom it may concern:

Be it known that I, FRED S. McATEE, a citizen of the United States, residing at Lincoln, in the county of Lancaster and State 5 of Nebraska, have invented certain new and useful Improvements in Supplemental Air Valves, of which the following is a specification.

The device relates to air valves and has as 10 an object the provision of a supplemental valve to allow air to enter the intake manifold of a gasoline engine when the speed of the air flowing through the manifold produces suction of a predetermined amount. 15 A further object of the invention is the provision of a valve of the class described which will allow a graduated amount of air to enter, increasing as the suction increases.

An illustrative embodiment of the invention 20 is shown in the accompanying drawing, in which the figure is a vertical longitudinal section through an embodiment of the invention, the parts being shown in elevation.

25 As shown, the device comprises a tubular body 10 of general T outline having a valve chamber 28 therein, and a projection 11 screw threaded, as at 12, which is adapted to be screwed into an opening in an intake manifold. The branch 13 of the T is shown as internally screw threaded and provided with a plug 14. The opening closed by the plug 14 is provided for the purpose of machining the valve seat 15.

35 The valve seat 15 and its coacting valve 16 are shown as provided with co-acting surfaces each comprising a portion of a sphere. Projecting from the valve head 16 there is shown a stem 17, perforated as at 18, for engagement with a spring 19 adapted to hold the valve to its seat.

To provide an anchorage for the spring 19 there is shown a projection 20 from the body 10, having an upturned extremity 21 perforated and screw threaded for the reception of an anchor 22. The anchor screw 22 is shown as perforated at 23 for engagement with the remaining end of the spring 19.

40 To hold the screw 22 in adjustment, a lock nut 24 is preferably provided and the head 25 of the screw is shown as slotted at 26 for engagement by a screw driver. To adjust the tension of the spring 19 the lock 45 nut 24 may be loosened and the screw 22

turned in the portion 20 so as to provide the desired tension upon the spring.

It may be desirable to supply hot air by means of the device. To this end a pipe 27, shown in dot and dash lines, may be slipped over the projection 20 into engagement with the body 10 of the device, which pipe may lead to a stove about the exhaust manifold of the engine.

The spring 19 is preferably so adjusted as 65 to tension that the device will only operate when the engine is turning at a high speed, under which condition the suction of the air passing rapidly through the carburetor usually draws more gasoline than is correct for 70 the load upon the engine. At this point in the operation of the engine the tension of the spring 19 will be overcome and the valve 16 will open to allow supplemental air to enter the intake manifold. The amount of air 75 thus allowed to enter will be graduated in accordance with the speed of the air into the intake manifold and the consequent suction exerted thereby.

Minor changes may be made in the physical embodiment of the invention without departing from its spirit. 80

I claim:

1. A supplemental air valve comprising, in combination, a body having a valve chamber, a tube projecting from said chamber adapted to be connected with the intake manifold of an internal combustion engine, a wall of said chamber having an opening therein surrounded by a valve seat, an inwardly opening valve coacting with said seat and having a stem projecting through said opening, an anchor supporting projection integral with said body, an anchor supported by said projection, a tension spring anchored to said anchor and said valve stem and adapted to retain said valve normally upon its seat. 85

2. A supplemental air valve comprising, in combination, a body of generally T form having a valve chamber therein and a tubular projection adapted to be placed in communication with the intake valve of an internal combustion engine, a screw plug engaging one branch of said body, a valve seat in a branch opposite said screw plug, a valve cooperating with said seat and having a stem projecting through the valve opening, an anchor supporting projection integral with said body, an angularly projecting ex- 105 110

2
tremity upon said projection, an anchor in screw threaded engagement with said extremity, a tension spring engaging said anchor and said valve stem whereby the valve 5 stem will be yieldingly held upon its seat.

3. A supplemental air valve comprising, in combination, a body of generally T form having a valve chamber therein and a tubular projection adapted to be placed in communication with the intake valve of an internal combustion engine, a screw plug engaging one branch of said body, a valve seat 10 in a branch opposite said screw plug, a valve

cooperating with said seat and having a stem projecting through the valve opening, 15 an anchor supporting projection integral with said body, an angularly projecting extremity upon said projection, an anchor in screw threaded engagement with said extremity, a tension spring engaging said anchor and said valve stem whereby the valve 20 stem will be yieldingly held upon its seat, and a pipe surrounding said anchoring projection and engaging said body adapted to convey heated air to said valve.

FRED S. McATEE.
